ALONZO PALMER, OF HUDSON, MICHIGAN, ASSIGNOR TO HIMSELF
AND N. H. MELCHER.

Letters Patent No. 84,754, dated December 8, 1868.

IMPROVEMENT IN PUMPS.

The Schedule referred to in these Letters Patent and making part of the same.

To all whom it may concern:

Be it known that I, ALONZO PALMER, of Hudson, in the county of Lenawee, and in the State of Michigan, have invented certain new and useful Improvements in Pumps; and do hereby declare that the following is a full, clear, and exact description thereof, reference being had to the accompanying drawings, and to the letters of reference marked thereon.

In the annexed drawings, making part of this specification,

A represents a pump, tube, or stock, of any convenient size, and closed at its lower end.

C represents a cylinder, which is open at both ends, and is made of wood, metal, glass, or other suitable material, and is connected centrally with the stock A, by means of a channel or tube, B.

E represent two valve-plates, made of metal, and secured within the cylinder C, at equal distances on each side of its centre pipe or channel B.

The cylinder is made a little smaller at these points, so as to give opportunity for more securely fastening the plates E.

The two plates E E are connected by a tubular bolt, H, which runs from the centre of the one to the centre of the other.

Through this tubular bolt passes a rod, I.

J K and J' K' represent metallic disks, which are secured upon the rod H, on each side of the plates E E, being rigidly attached to said rod.

The disks K K' are perforated, so that water will pass through them freely, while the disks J J' are solid, and act as valves.

G G' represent wooden or other suitable rings, which are placed between the disks J and K, and J' K', having packing upon their peripheries, to make them fit

snugly within the cylinder. These rings are less in thickness than the distance between the disks J and K, and serve as seats for the solid valves or disks J J'.

As the rod I moves upward, the disk K is brought in contact with the ring G, while a space is left between the ring and disk for water to enter.

As the rod descends, the disk J is brought in contact with the ring, thus closing this opening and forcing the water below it through plate E, and into pump-stock.

A disk, of leather, is secured to each of the inner faces of the plates E, and act as valves, to allow water to enter the chamber O.

The cylinder C is immersed, so that it receives water from each end.

By working the rod I backward and forward in the cylinder, water is thus alternately received through the valves J and J', and forced through the plates E E into chamber O, and up the stock, through pipe B.

The rings G G' move in the cylinder, as they are forced by the disks J K and J' K', the openings through said rings being alternately closed and opened, as above described, by the disks or valves J and J'.

Having thus fully described my invention,

What I claim, is—

The disks J K and J' K', in combination with the rings G G', bolt H, rod I, and plates E E, with their valves, arranged and used as and for the purposes set forth.

In testimony that I claim the foregoing, I have hereunto set my hand, this 10th day of September, 1867.

ALONZO PALMER.
